UNITED STATES PATENT OFFICE.

JOHN HOEY, OF SAN FRANCISCO, CALIFORNIA.

WIRE BED-BOTTOM.

SPECIFICATION forming part of Letters Patent No. 697,087, dated April 8, 1902.

Application filed May 17, 1901. Serial No. 60,667. (No model.)

To all whom it may concern:

Be it known that I, JOHN HOEY, a citizen of the United States, residing in the city and county of San Francisco, State of California, 5 have invented an Improvement in Wire Bed-Bottoms; and I hereby declare the following to be a full, clear, and exact description of the same.

My invention relates to improvements in 10 bed-bottoms of that class in which the bearing-surface is composed of woven wire.

The object of this invention is to combine two 15 elastic and essentially parallel, separate, and horizontal fabrics in a bed, so that all the desirable qualities of the readily-yielding upper fabric may, when the weight is increased, be supplemented by a second and preferably less yielding surface below, and in conjunction with these of a continuous yielding pad or 20 mattress of substantially even thickness interposed between the entire surfaces, so as to gradually transmit the pressure from the upper to the lower one.

My invention also comprises details of construction, which will be more fully explained 25 by reference to the accompanying drawings, in which—

Figure 1 is a portion of an underneath plan of my invention. Fig. 2 is a longitudinal 30 section at $x x$ of Fig. 1. Fig. 3 is a plan showing a modification. Fig. 4 is a longitudinal section at $y y$, Fig. 3.

When woven-wire mattresses are made 35 of light material, they will sag under considerable weight and soon get out of shape, besides being very uncomfortable for the occupant on account of the sinking of the central portion, and if the fabric is woven sufficiently stiff to bear the weight placed upon it it is too 40 unyielding and hard for comfort.

It is the object of my invention to so combine the upper mattress with a yielding support, so located with reference to it that it receives the weight when the upper mattress 45 has been slightly depressed.

Another object of my invention is to provide a tension upon the lower side of the end bars, so that the tension of the mattress stretched across the upper side will be in a 50 measure counterbalanced and the tendency of the end bars to turn by reason of a strain

entirely upon one side will be counteracted.

In my present invention I have shown the side bars A and the end bars B. For certain 55 classes of beds the side bars may rest upon the cross-slats of the bed and the end bars are raised above the side bars by means of blocks 2, so that the mattress will be brought above the rails of the bedstead, and the end 60 bars may also be projected, so as to overhang these rails and bring the edges of the mattress out flush therewith. In other constructions the end bars may be bolted directly to the top of the side bars and the blocks 2 65 may be located below the ends of the side bars in order to raise the mattress to the desired height. I have illustrated both these constructions in showing my invention.

3 is the upper woven-wire mattress, which 70 is stretched across the top of the end bars B and bent over the outer edges, where it is secured by staples or other suitable fastening, and when the mattress is complete these ends may be covered by a supplemental strip, as 75 at 4, which conceals the raw edges and at the same time assists in securing the fabric by the short bend at right angles, which is made over the upper outer edge. When the fabric has been thus stretched and weight is 80 put upon it, the entire strain is brought upon the upper sides of the end bars, and the tendency is to twist these bars about the bolts 5, which secure them to the side bars. In order to counteract this tendency, I have 85 shown the supplemental supports 6 and 7, which are extended below the end bars, turning upwardly over the outer edges and being secured in the same manner as the woven-wire upper fabric. As shown at 6, these sup- 90 ports consist of elastic cables, which are stretched longitudinally beneath the end bars and at a distance from the upper fabric equal to the thickness of said bars. These cables are then drawn toward each other transversely by links or clips, as at 8. The cables next adjacent to the side rails are secured to the rails at intervals by staples. The portion midway between each pair of staples is then drawn transversely and connected with the 95 corresponding portion of the next adjacent cable by clips, as at 8. This cable is again

connected with the third in line transversely with the staples which secure the first cable to the side rail by clips, as at 8^a, and the next cable is again connected with this one by 5 clips 8^b, thus alternating from one side to the other of the bed-bottom and producing a series of elongated diamond-shaped spaces between the cables. These cables are thus all stretched to any desired degree of tension and 10 exercise a pull upon the lower side of the end bars which counteracts the strain of the upper woven-wire fabric.

As shown in Fig. 3, the lower structure is made of woven-wire fabric instead of the 15 cables of Fig. 1, and this fabric is preferably heavier and stiffer than the upper one. In this case the fabric is stretched across the lower sides of the end bars, upturned at right angles over the outer edges, and secured, by 20 staples and the strip 4 in the same manner as the upper fabric. The tension thus counterbalances the strain on the end bars.

When weight is placed upon the upper fabric, it will be depressed and will gently come 25 into contact with the lower fabric, which thus adds its strength and elasticity to support the weight upon the bed and to prevent the latter sinking to a greater extent than is desirable.

30 In some cases it may be found desirable to insert some soft fabric, such as a thin pad *a*, of resilient material, which will tend still further to preserve the buoyancy and shape of the bed.

Having thus described my invention, what 35 I claim as new, and desire to secure by Letters Patent, is—

1. The combination in a bed-bottom of a rigid rectangular frame, two superposed elastic fabrics, stretched between said frame and 40 one of said fabrics serving as a reinforce for the other, and a continuous yielding pad or mattress parallel with and interposed between the entire inner surfaces of the two fabrics, and adapted to gradually transmit the 45 pressure of the upper fabric to the lower one.

2. The combination in a bed-bottom, of a rigid rectangular frame composed of side and end bars, parallel elastic fabrics stretched upon opposite sides of the frame so as to leave 50 a clear uninterrupted space between the fabrics, one of said fabrics having a different degree of flexibility than the other and serving as a reinforce for the latter, and as a means for counterbalancing the strain of the other fabric upon the end bars of the frame, and a pad extending parallel with the fabrics and through the space between them, and adapted to gradually transmit to the lower fabric, substantially throughout its length, the pressure 55 of the upper fabric.

In witness whereof I have hereunto set my hand.

JOHN HOEY.
